Attorney

UNITED STATES PATENT OFFICE.

FRITZ GENTZCKE, OF ZEESEN, NEAR KONIGS WÜSTERHAUSEN, GERMANY, ASSIGNOR
TO LUFTFAHRZEUGBAU SCHUETTE-LANZ, OF MANNHEIM-RHEINAU, GERMANY.

LANDING APPARATUS FOR AIRSHIPS.

Original application filed October 8, 1923, Serial No. 667,323. Divided and this application filed February 8, 1924. Serial No. 691,530.

To all whom it may concern:

Be it known that I, FRITZ GENTZCKE, a citizen of the Republic of Germany, residing at Zeesen, near Konigs Wusterhausen, Germany, have invented certain new and useful Improvements in Landing Apparatus for Airships; and I do hereby declare the following to be a full, clear, and exact description of the invention, such as will enable others skilled in the art to which it appertains to make and use the same.

This application is a division of my application filed October 8, 1923, Serial No. 667,323.

15 The invention relates to so-called landing feet for use in airships to permit the airship to be cushioned in landing. Hitherto, shock absorbers have been employed in connection with airships for breaking or cushioning purposes in case of concussion or impact on the ground in the shape of air-filled containers made of rubberized cloth, bags filled with rubber bulbs or the like, wickerwork, or piston brakes and dash-pots. All of such 20 means are, however, objectionable for the reason that they increase the resistance of the air during the voyage and further because they fail to work satisfactorily on landing and fail to adjust or conform to the 25 yawing or drift of the ship.

The present invention provides an improved landing foot which in its essentials comprises a lever having a longer arm and a shorter arm, said lever being fulcrumed on a horizontal axis in such manner that the longer arm thereof will come in contact with the ground on landing, while the shorter arm is connected to energy-absorbing devices which will function to cushion the airship in landing. The levers and energy-absorbing devices are connected to a support which is movable about a vertical axis whereby the lever has movements not only in a vertical plane but also in a horizontal plane, thus adapting the landing foot to various service conditions.

50 The various features of novelty and invention will appear from the detailed description taken in connection with the accompanying drawings forming part of this specification.

In the drawings, Fig. 1 is a view showing the lever of the landing foot in side eleva-

tion and the energy-absorbing means in vertical section;

55 Fig. 2 is a view taken at right angles to that shown in Fig. 1; and

Fig. 3 is a modified form of the energy-absorbing means.

The landing foot comprises in the main a lever 17 having fulcrum points 18, 19 and 20 at one end thereof and a ground engaging member 27 at the other end.

The bottom of the airship or cabin is indicated at 25 and suitably mounted therein for turning about a vertical axis is a support or casing 26. The top of the casing or support preferably works against ball bearings 24, and disposed around the circumference of the casing is a row of ball bearings 23. The lever 17 is pivoted at 20 to a member 28 depending from said casing or support in a manner to permit horizontal swinging thereabout. Inasmuch as the support or casing is movable about a vertical axis it will now be seen that the lever has movement about such axis and also about a horizontal axis.

The preferred form of energy-absorbing means is a pair of dash-pots 21 having suitable pistons, the latter being connected by means of links 22 to the points 18 and 19 on either side of the rocking fulcrum 20 of the lever 17.

The energy-absorbing means may take the form of a rotary dash-pot instead of the reciprocating type shown in Figs. 1 and 2. The rotary type of shock absorber is shown in Fig. 3 and comprises vanes or radial members 30 and 31 operating on either side of 32 (only one shown) and 33 extending radially from the casing or support. This type of shock absorber is known in the art and need not be further described.

The ground engaging means is shown as a shell-shaped or hemispherical body and the same is intended to represent any suitable type of ground engaging means. The ground engaging means may take the form of an air cushion or rolling means suitably attached and cushioned to the lever 17 as will be readily understood.

As will now be readily understood by those skilled in the art, the landing foot is adapted to cushion any shocks imparted to the airship by striking the ground on land-

- 2
- ing, thus avoiding excessive strain on the structure or framework of the ship. Inasmuch as the landing foot is mounted to turn about a vertical axis as well as about a horizontal axis 20 the landing foot will automatically adjust itself to the horizontal movement of the airship with respect to the ground. Such adjustment is greatly facilitated by the fact that at the very moment of touching or striking the ground the cushioning effect of the landing foot or lever is still quite small but gradually increases in accordance with the increasing resistance offered by the energy-absorbing means.
- 15 Furthermore the movability of the landing foot or lever about the axis 20 permits the same to readily be withdrawn to an in-

active position under the body of the airship whereby the same will not be unduly exposed to the opposing action or resistance 20 of the air.

What I claim is:

A landing device for airships comprising a turnable support, a lever pivoted to said support, a ground engaging member at one end of the lever, and energy-absorbing means on either side of the pivot of said lever, said means including chambers depending from said support and devices associated with said lever for operation with 25 in said chambers.

In testimony whereof I affix my signature.

FRITZ GENTZCKE.
